UNITED STATES PATENT OFFICE.

WILLIAM M. GOLDSMITH, OF CINCINNATI, OHIO.

PROCESS FOR MAKING DOMES FOR PLASTIC CONSTRUCTION.

Application filed March 22, 1922. Serial No. 545,829.

To all whom it may concern:

Be it known that I, WILLIAM M. GOLDSMITH, a citizen of the United States of America, and resident of Cincinnati, in the county of Hamilton and State of Ohio, have invented a new Process for Making Domes for Plastic Construction, of which the following is a specification:

An object of my invention is to expedite the manufacture of domes or arched forms of the type that are used in plastic construction, such as reinforced floors, etc.

Another object is to simplify the manufacture of such domes.

These and other objects are attained by the means described therein and disclosed in the accompanying drawings in which:

Fig. 1 is a perspective view of a dome made in conformity with my process, parts 20 of the dome being broken away.

Fig. 2 is a sectional view of line 2—2, on a reduced scale.

Fig. 3 is a sectional view of one of the sides of a dome.

Fig. 4 is a plan view of a series of sides interlocked with one another preparatory to the mounting of the top or closure on such sides.

My process contemplates a number of side plates 1, which may be secured upon one another in the manner shown in Fig. 4, and over which a top plate may be placed, whereupon those parts of the top and side plates which engage, have pressure exerted upon them so as to squash the engaging parts upon one another, thereby locking the side plates and top plate upon one another.

The side plates 1, at their opposite ends, are turned upon themselves whereby U-shaped flanges 3 and 4 are formed at such ends. The flanges 3 and 4 are turned upon opposite sides of the side plates. The side plate is then turned upon itself adjacent the flange 4 so as to form a U-shaped groove 6, which groove extends toward the same side of the side plate 1 as does the flange 3, the open end 7 of the groove 6 opening toward that side of the plate 1 opposite to the side upon which the flange 3 lies. A flange 8 is formed along the upper edge of the plate 1, and extends in the direction opposite to that in which the flange 3 extends. All of the side plates are constructed in this manner whereby any flange 3 on any side plate may be inserted into the U-shaped groove 6 of any other side plate, whereby there is at-

tained a polygonal-walled tubular structure comprising a series of side plates, the flanges 8 on all of the side plates extending outwardly. The top plate 2 has its side edges 9 turned downwardly upon itself so as to form U-shaped grooves 10, the grooves being slightly wider than the thickness of flanges 8 on the plates 1. The cover or top is then slid over the sides in such manner as to lodge the flanges 8 upon two of the opposite sides of the structure as shown in Fig. 4, in the grooves 10 formed upon opposite sides of the top plate. This is possible by slightly springing the one end of the top over the ends of the opposed flanges to start the top over the tubular structure. The slight play resultant from making the grooves slightly wider than the flanges readily permits such assembly. The top is slid over the form shown in Fig. 4 until the flange on the side plate transverse to the movement of the top and over which the top plate is moved, has lodged in its complementary groove 10 in the top, as shown in Fig. 2. This then leaves the flange in the side plate towards which the top was being moved, to be seated in its complementary groove in the top plate. The edges of the top plate 2 are turned over to an extent such that the overturned edge of the top which forms the groove into which the flange on the side plate which is to be seated lastly, will just clear such flange. The whole form is then placed over a suitable squashing die and the several flanges are turned over edges are squashed upon one another, whereby the several elements are locked upon one another. It should be observed that the grooves 10 are slightly wider than the thickness of the flanges 8 and have lower ends extending inwardly toward the center of the form, whereby the ends of the lower walls of the grooves in the top plate will be moved further centerward and all such lower walls will because of the reduction in width of said grooves from the action of the squashing die, assume positions in engagement with the undersurfaces of the flanges 8 formed on the side plates. It is readily apparent that by modifying the relative sizes of the flanges and the depth and width of the grooves the undeturned edge of the top that was referred to as being sprung over the opposed flanges may be caused to assume a position in alignment with or below its immediately adjacent flange. Either

structure will serve to lock the top on the tubular form. Whereas there would be no occasion to remove the top from the tubular form, the squashing might be dispensed with, although then the top would not serve as efficiently for effecting a rigid tubular side structure.

If desired, the side plates and top plate may be corrugated in any of the manners well known in the art, whereby the plates may be strengthened, without interfering with the application of my process. Also the side plates may be secured upon one another in any well known manner, prior to affixing the top plate thereupon.

I claim—

1. The process of making domes for use with concrete floor construction and the like comprising forming a flange on one side 20 and **U**-shaped grooves at opposite ends of plates, inserting a wall of each plate in the groove in the next adjacent plate, whereby a polygonal walled tube is formed, the plates having their flanges extending outwardly, forming a top with **U**-shaped grooves for the reception of the flanges on the plates, sliding the top over the tube and locking the flanges in the grooves in the top, and squashing the walls of all of the grooves 30 whereby the plates and top are secured upon one another.

2. The process of making forms for use in concrete floor construction and the like comprising forming plates each with a flange along one edge and with **U**-shaped grooves at its ends, the grooves opening on opposite sides of the plates and having their walls offset toward the same side of the plates, the depth of the grooves extending 35 at an angle one to the other, assembling a series of plates by inserting a wall of one groove on one plate in a groove on the next plate, the walls of all the grooves opening 40 on a given side of the plates being inserted in the grooves on the opposite side of the next adjacent plate, whereby a polygonal walled tube is formed, the plates having

their flanges extending outwardly, forming a top with **U**-shaped grooves along its edges, all said grooves lying on a common side of 50 the top, and being of a width in excess of the thickness of the flanges on the plates, the free edges of the walls of the grooves on two opposite sides of the top being spaced a distance slightly in excess of the 55 distance between the outermost edges of the flanges disposed on opposite sides of the tubular structure, sliding the top transversely of the tube by inserting flanges on the plates in grooves on the top and moving the 60 top over one of the flanges and toward the other of the flanges, the distance of which last two mentioned flanges, is slightly less than the distance between the mentioned 65 edges of the grooved walls on the top, and disposing the flanges and the walls of the grooves on the top in such relationship that the top is locked against withdrawal from the tubular form by means of said flanges and grooved walls.

3. A process for mounting a top plate upon a side plate structure having outwardly extending flanges along its upper edge, comprising forming a top plate with **U**-shaped grooves along its edges, all said 70 grooves lying on a common side of the top plate and being of a width in excess of the thickness of the flanges on the side plate structure, the edges of the grooves at opposite sides of the top plate being spaced at 80 a distance slightly in excess of the distance between the outermost edges of the flanges on opposite sides of the side plate structure, inserting the flanges on opposite sides of the side plate structure in oppositely disposed 85 grooves in the top plate, sliding the top plate over the side plate structure until all the flanges lodge in grooves in the top plate, and squashing the walls of the grooves, whereby the top is locked upon the flanges. 90

In testimony whereof, I have hereunto subscribed my name this 21st day of March, 1922.

WILLIAM M. GOLDSMITH.
